(57) **CLAIM**

The ornamental design for a portion of a mesh drawer, as shown and described.

DESCRIPTION

FIG. 1 is a perspective view of a first embodiment of a portion of a mesh drawer showing our new design;

FIG. 2 is a front view thereof;

FIG. 3 is a rear view thereof;

FIG. 4 is side view thereof, the opposite side view being identical thereto;

FIG. 5 is a top view thereof;

FIG. 6 is a bottom view thereof; and,

FIG. 7 is a perspective view of a second embodiment of a portion of a mesh drawer showing our new design.

The jagged broken lines surrounding the U-shaped opening in each of the four side walls of the mesh drawer represent boundaries of the design claimed, and form no part of the claimed design. The jagged broken lines at the bottom of the corners represent boundaries of the designs claimed and also form no part of the claimed designs. The mesh material shown along the bottom of the four side walls of the drawer, and the mesh material shown on the bottom of the drawer, is shown in broken lines and forms no part of the claimed design.
